UNITED STATES PATENT OFFICE.

ALOIS B. SALIGER, OF NEW YORK, N. Y., ASSIGNOR TO SALIGER SHIP SALVAGE CORPORATION, OF NEW YORK, N. Y.

BURROWING-MACHINE.

1,372,317.

Specification of Letters Patent.

Patented Mar. 22, 1921.

Application filed February 20, 1919. Serial No. 278,166.

To all whom it may concern:

Be it known that I, ALOIS B. SALIGER, a citizen of the United States, residing at New York, county of New York and State of New York, have invented certain new and useful Improvements in Burrowing-Machines, of which the following is a specification.

My invention relates to apparatus for penetrating or burrowing into the ground, being more particularly applicable to burrowing into submerged or otherwise not readily accessible ground, as for instance for the purpose of passing under the hull of a sunken vessel so as to carry a chain or rope thereunder in connection with efforts to salvage the same; the device may also be used for laying wires, cables or tubes under streets, buildings or other structures, for prospecting for water, oil or minerals, and various other purposes.

The object of my invention is to provide a burrowing apparatus which shall be simple in construction, durable, efficient in operation, and which shall be capable of being operated and guided from a distance at the will of the operator.

The invention consists in the novel construction, arrangement and combination of various devices and parts, as set forth in the claims forming part of this specification, one embodiment of such apparatus being herein described and illustrated in the accompanying drawings.

In the accompanying drawings, Figure 1 is a longitudinal vertical section taken along the line 1—1 of Fig. 2, and showing the general construction of the machine; Fig. 2 is a top view; and Fig. 3 is a transverse vertical section taken along the line 3—3 of Fig. 1.

In carrying my invention into effect in the embodiment thereof which I have selected for description in this specification and for illustration in the accompanying drawings I provide a frame-work 1, of the general shape as indicated in Fig. 1. In this frame I dispose the shafts, 2, 3 and 4, journaled in suitable bearings. The shafts 2 and 3 carry pulleys 5 and 6. On the shaft 4, are disposed sprocket wheels 7, also the driving gear 8. An endless chain or belt 9, having on its outer surface fins or grippers 10, is adapted to run over the pulleys 5 and 6, and the sprockets 7 at the upper and lower

parts of the apparatus respectively. The driving gear 8, which is secured on the shaft 4, is actuated by means of the worm gear 11, on the motor shaft 12, the free end of which is journaled in the bearing 13. The motor 14, may be of any type suitable for the purpose, but I prefer to use a hydraulic turbine motor. In Fig. 1, I indicate such a motor, and in which 15 represents the intake pipes and 16 the exhaust pipe. 17 is a tank forming the tip or the front part of the framework 1, and which contains multiple chambers which are preferably oppositely disposed to each other. This tank has through its outer walls, nozzles or slits 18, disposed as indicated and pointing in slightly different directions in fan shaped manner. The exhaust pipes 16, are connected with these chambers in the tank 17, and in a crossed manner. In other words, the exhaust pipe 16 of the lower motor is connected with the upper chamber in said tank and vice versa. This arrangement enables the operator to control the direction in which the machine travels as explained below. The intake tubes 15, which are of flexible construction, may extend for any reasonable distance from the machine and terminate in a source of supply not shown in the drawings, but which in practice consists preferably of a tank of fluid kept under constant high pressure by means of a suitable pump. The cocks 23, are adapted to partially or completely cut off the pressure on either of the intake tubes 15. The water or other fluid passing through the intake tubes 15, while under pressure actuates the motors 14, and passes out through the tubes 16 and the openings 18. It is intended that said water or other fluid in passing through the motor 14 should lose only a part of its pressure, so that when it passes out through the openings 18, it shall still do so with great force. Powerful streams of water playing against the obstructions through which the machine must burrow its way, have the effect of dislocating and disintegrating such obstructions. It will be apparent that by simply diminishing or cutting off the supply of power by means of the cock 23, from one of the intake tubes, the machine will change its direction precisely as a row boat does by pulling only one oar instead of both. The part 21, is a suitable eye bolt to which may be conveniently secured a cable or other fittings, and 22,

shows a cable so secured thereto. The part 19, is a tube which is connected to the intake tube 15, and so located that a powerful spray of water from the nozzles 20, may be directed 5 against the endless belts 9, at the point where they pass over the pulleys 6, for the purpose of dislodging any obstructions which may cling to it and prevent such obstructions from being passed into the machine, thus 10 obviating jamming or otherwise interfering with its proper operation.

The advantages of my invention will be obvious from what has been above said with regard to the construction and mode of operation.

I do not confine myself to the construction herein described and shown, as it is obvious that various modifications may be made therein without departing from the spirit 20 and scope of my invention.

While in the drawings I show only two traction belts or surfaces oppositely disposed, which for most purposes is sufficient, it is obvious that a larger number of such 25 independently operated traction surfaces may be employed. In other words 3, 4, 6 or more such units could be disposed around a common center where special conditions might require it without changing the principle 30 of operation or departing from the spirit of the invention. In cases where more than two traction units are employed, the tank 17, would have a corresponding number of chambers, and would preferably be triangular, square or hexangular in shape as 35 the case may be, or these chambers could be independent of each other, and correspondingly disposed. The idea being that each of these chambers or tanks is simply the 40 outlet or nozzle of the exhaust pipe of one of the traction units, with said nozzle placed in a general direction opposite to said traction surfaces.

What I claim is:

45. 1. A burrowing machine comprising in combination a housing, a traction belt located partly within said housing and partly outside of the same, and means adapted to operate said traction belt.
50. 2. A burrowing machine comprising in combination a housing, a traction belt located partly within said housing and partly outside of the same, and means adapted to operate said traction belt, said traction belt being provided with ridges adapted to increase the tractive power of said belt.
55. 3. A burrowing machine comprising in

combination a housing, a traction belt located partly within said housing and partly outside of the same, means adapted to operate said traction belt, and means adapted to sluice out obstructions in the line of travel of said machine.

4. A burrowing machine comprising in combination a housing, a traction belt located partly within said housing and partly outside of the same, and means adapted to operate said traction belt, comprising a drive sprocket engaging said belt and a motor operatively connected with said sprocket.

5. A burrowing machine comprising in combination a housing, a plurality of traction belts each located partly within said housing and partly outside of the same, and means adapted to operate said traction belts independently of each other, whereby the direction of motion of said machine may be controlled.

6. A burrowing machine comprising in combination a housing, and means for propelling said housing, comprising a plurality of traction belts each located partly within said housing and partly outside of the same, means adapted to operate said traction belts comprising a hydraulic motor and fluid supplying means therefor, and means adapted to sluice out obstructions in the line of travel of said machine, comprising exhaust ports from said motors adapted to discharge the fluid for operating same forward of the machine.

7. A burrowing machine comprising in combination a housing, and means for propelling said housing, comprising a plurality of traction belts each located partly within said housing and partly outside of the same, means adapted to operate said traction belts comprising a hydraulic motor and fluid supplying means therefor, and means adapted to sluice out obstructions in the line of travel of said machine, comprising exhaust ports from said motors adapted to discharge the fluid for operating same forward of the machine, said motors being operable and controllable independently of each other.

In testimony whereof, I have signed my name to this specification in the presence of two subscribing witnesses, this 18 day of Feb., 1919.

ALOIS B. SALIGER.
